UNITED STATES PATENT OFFICE.

JOHN C. BROOKS, OF PATERSON, NEW JERSEY.

NEEDLE-LOOM.

No. 902,203.

Specification of Letters Patent.

Entered Oct. 27, 1908.

Application filed January 18, 1902. Serial No. 90,273.

To all whom it may concern:

Be it known that I, JOHN C. BROOKS, a citizen of the United States, residing at Paterson, in the county of Passaic and State of New Jersey, have invented certain new and useful Improvements in Needle-Looms, of which the following is a specification.

My invention relates to the needle used to insert weft, and the object of my invention is to provide such needles with means to detect the abnormal position of warp threads said means being actuated by such warp threads, and in conjunction with weft stop devices, operate to stop the loom.

15. A further object of my invention is to provide such needles with means to engage with and disengage from needle operating mechanism, said means being engaged with such operating mechanism when the needle rests 20 in the line of travel of the said operating mechanism, and a further object is to provide the needle with means to resist accidental misplacement when being carried out of the line of travel of the operating mechanism. I attain this object by mechanism 25 shown in the accompanying drawings, in which,

Figure 1 is a view in side elevation, broken to save space, and broken out to show details of construction, of a weft inserting needle embodying my invention. Fig. 2, is a plan view of the parts shown in Fig. 1. Fig. 3 is a view in vertical cross section on the line 3—3 of Fig. 1, looking in the direction of the arrows, this view showing a convenient and preferred cross sectional construction of a needle.

The needle is indicated by letter A. For the purpose of securing rigidity and lightness the needle in cross section has the form of a "Greek cross," although other cross sectional forms, which will serve to attain the desired lightness and rigidity, may be employed. The butt end of the needle is provided with a pin, c, which is designed to be engaged by a picker, or other mechanism, to insert and withdraw the needle from the shed, and engage with and disengage from said actuating mechanism. Also attached 45 to the butt end of the needle is a light spring b, which by frictional engagement with the guides at the end of the lay, serves to keep the needle from accidental misplacement, when not in active contact with the actuating mechanism. Near the forward or point-

ed end of the needle a vertical mortise d is cut, and there is provided also a thread delivering eye, e, which passes through the needle, from front to back and intersects the aforesaid vertical mortise. On a pin f 60 at the end of the mortise farthest from the thread delivering eye is pivoted a detector g, moving in a vertical plane. The free end of this detector crosses the line of travel of the weft thread in its movement through 65 the delivering eye, and such free end is provided with a cutting edge h. As shown in the drawing, the said detector is curved at its outer side and projects slightly above the lines of the needle. A spring i secured in 70 the mortise, d, engages and holds the detector in its elevated position, and normally prevents the detector from interfering with the passage of the weft through the delivering eye.

As is well known, upon the occurrence of a float in the warps, the warp shed is contracted at that point, and such abnormally positioned warp threads would bear upon the exposed surface of the detector g and depress the free end of the same within the mortise, so that the cutting edge h would sever the weft, and free it from its tension, under which it operates, and stop devices of any suitable nature, would respond to the 85 action of the slackened weft, and stop the loom. The needles, if carried in a series of boxes in lieu of shuttles, would as the shuttle-box-shifting mechanism shifted the boxes, be brought into the line of travel of 90 the picker and the pin c would be engaged with the picker and the needle caused to slide within its box and project its end between the warp shed; as the needle was shifted away, from contacting with the 95 picker, the spring b would hold the needle in an assumed position during the inactivity of the needle.

Having described my invention, I claim as new, and desire to secure Letters Patent 100 for—

1. In a loom, a filling inserting needle provided with means to engage with and disengage from its actuating means and a yieldable device upon the needle to hold the needle in a predetermined position when not in operation.

2. In a loom, a needle to insert weft provided with means to resist accidental misplacement and with means to enable the nee- 110

dle to engage with and disengage from actuating means.

3. The combination in a filling inserting needle of means upon the needle to enable the needle to engage with and disengage from its actuating means, means upon the needle to enable the needle to flexibly lock itself in a predetermined position, with means within the needle to detect a float

and sever the weft thread upon the occurrence of a float.

In testimony whereof I have signed my name in the presence of two subscribing witnesses.

JOHN C. BROOKS.
